MEANS FOR PREVENTING PITCHING OF SHIPS

Filed April 13, 1927

UNITED STATES PATENT OFFICE

ELMER A. SPERRY, OF BROOKLYN, NEW YORK, ASSIGNOR TO THE SPERRY GYROSCOPE COMPANY, OF BROOKLYN, NEW YORK, A CORPORATION OF NEW YORK

MEANS FOR PREVENTING PITCHING OF SHIPS

Application filed April 13, 1927. Serial No. 183,275.

This invention relates to automatic means for lessening the pitching of ships. The prevention of rolling in ships has long been known and is usually accomplished by a 5 large gyroscopic stabilizer which suppresses rolling by direct gyroscopic reaction. Such a means, however, is not feasible for preventing pitching on account of the very much greater mass moment of the ship 10 about its axis of pitch than about its rolling axis. According to my invention, I propose to suppress pitching by locating small diving rudders near the bow of the ship, and possibly also at the stern, and providing 15 automatic means for turning or feathering these rudders in such a way that they impose a counter pull of large magnitude whenever the bow is rising or falling. Means may also be provided for withdrawing 20 the rudders flush with the skin of the ship and also for varying the amount of feathering in accordance with the amplitude of pitch. Both of these features are important as they reduce the head resistance 25 to a minimum. Preferably the rudders or fins and also the operating mechanism therefor are placed within the bulbous bow which is now provided on many large ships 30 so that the head resistance of the ship is not increased.

Referring to the drawings in which what I now consider the preferred form of my invention is shown:

Fig. 1 is a sectional elevation through the bulbous bow of the ship showing my invention mounted therein.

Fig. 2 is a front vertical section taken just inside the bow of the ship as shown in Fig. 1.

Fig. 3 is a horizontal section taken just below the roof of the water-tight compartment shown in Fig. 1.

Fig. 4 is a detailed sectional view of a locking mechanism for centralizing the fins 45 before withdrawing the same into the bow.

Fig. 5 is a diagrammatic view of the side elevation of the ship showing the location of my invention thereon.

The rudders 1 and 1' are preferably balanced and protrude on each side of the bulbous bow 2 of the ship. Long rigid stems 3 and 4 protrude inboard from each side of the rudders and are secured in outboard half or split (top and bottom) journals 5 and full journals 6. These heavy stems can rotate as well as slip along in these 50 bearings to withdraw the rudders. Rack bars 7 and 7' and pinion sectors 8 and 9 serve to rotate the stems slightly and thus feather the rudders 1 and 1' by the action 55 of a servo motor, such as hydraulic cylinder 10. One end of lever 11 moves with the rack 7 or piston of cylinder 10, said lever being pivoted at its other end 11'. The cylinder 10 is provided with some form 60 of controller such as the usual balanced piston valve 12 having a stem 13 operated by floating lever 14 pivoted on one end of link 21 by a transverse pin thereon which extends through arcuate slot 22 in lever 14. 65 The other end of lever 14 is actuated by link 17 pivoted to the arm 18 (Fig. 4) which is connected to and operated by a friction clamp 19 on drum 20 and oscillates between 70 fixed stops 18' and 18''. Swinging link 21 75 connects levers 11 and 14. Its position in slot 22 is determined by the position of the scissors 23 shown in full lines in the middle position and in dotted lines in its two extreme positions, which mechanism is governed by the amplitude of the swing of pin 24 about the center of shaft 25 which is journalled in support 25' on base 30. This pushes the levers of the scissors freely 80 against the spring 26 on account of the valve 27 in the plunger 28 of the dashpot 29 being open on the down stroke. Also due to said valve and dashpot, the scissors close slowly but open freely. The position of the 85 scissor arms determines the position of the 90

link 21 in the groove 22 through the link 32, lever 65 pivoted at 66 and link 67 pivoted at one end to link 21 and at 16 to lever 65. As a gyroscopic baseline mechanism, I have shown at 33 a pneumatically damped gyroscopic pendulum which is maintained with a high degree of accuracy regardless of the plane of the ship. The vertical fore and aft plane is the one selected for the position of rack sector 34 on the gimbal 35 of the gyroscope, which is pivoted at 36 and cooperates with pinion 37 driving contact wheel 38. The cooperating contactor or trolley 39 is mounted on wheel 40, the axis of which is coincident with that of pinion 37 and which is driven from pinion 41 and ultimately from the follow-up motor 42. Pinion 41 also drives wheel 43 which carries the pin 24 on center 25 through an intermediate step down gears 44, 44'. The ratios are so chosen as to give the scissors 23 their maximum amplitude with the maximum amplitude of pitch of the ship.

The operation of the scissors mechanism will thus be readily apparent. Each time the vessel pitches the follow-up motor 42 actuates the pin 24 through the multiplying gearing at a much more rapid rate than the rate of displacement of the gyro with respect to the ship. The scissors open freely but close slowly and hence, depending upon the velocity of pitch, the said scissors will remain open for a longer or shorter period thus actuating the diving rudders for a longer or shorter period to counter-act the pitch. It will thus be seen that I utilize two factors for controlling the counter-acting movement of the diving rudders. The first of these is that due to the displacement of the gyro with respect to the ship when pitching occurs which operates link 17, and the second of these is the opening of scissors 23 which depends upon the velocity of displacement. Both of these factors control the degree of actuation of link 11 and hence of the rudders. I have, therefore, a system whereby I move a plurality of diving rudders in a direction to counter-act pitching, the said movement being a function of both the degree and the velocity of pitch.

The friction drum 19 is connected with the positively driven gear 40, which through the follow-up is made to rotate with every movement in elevation which constitutes the pitch. The follow-up motor 42 acts in response to the trolley 39 and the reversing contacts on wheel 38 in the usual manner. The foundation 30 moves with the ship whereas the gyro 33 and rack 34 refuse to move but stand in space actuating the contacts and instituting the positive follow-up motion which is used for reversing the feather of the rudders 1 and 1' at each end of the oscillation by drum 19 and to control the amount of feathering through the

promptness and extent of action of the valve follow-up gear for valve 13 which is controlled by the pin 24 acting through scissors 23 and connection 32.

Describing now another secondary function, the withdrawing mechanism shown in Fig. 3, consists of bell crank levers 44' and 44'', pivoted on the vertical stems 45, and geared together by gear sectors 61. Stems 45 pass up through the stuffing boxes 46 in wall 47 separating the water compartments below from the other parts of the ship. The outer ends of said levers 44' and 44'' operate in jaws 48 in each of the stems 3 and 4 and in swinging into their inner position (shown in dotted lines) withdraw completely the rudders 1 and 1' within the bulbous bow 2, the stems 3 and 4 sliding in their bearings as described. The hydraulic cylinder 49 effects this withdrawal, operating against the compression spring 50 through the action of the valve 51 which is held out of action by the circular portion 52, (also shown in Fig. 4), by slide 53 which also carries a pin 54 which engages a bell-mouthed slot 55 in clamp 19 where it is shown in dotted lines when down in the slot. It is only after the pin 54 is shifted into its extreme position within the slot that the circular part 52 of valve 51 may pass the end of slide 53 and, therefore, be released. The object of pin 54 is to accurately centralize the friction clamp 19 and lock the same in its central position regardless of drum 20. This means that the piston of cylinder 10 and racks 7 occupy their central positions and that the rudder plates 1 will then just slip into tight fitting slots 56 in the skin of the ship into which they may be quite well fitted thus filling the hole which exists when they are protruding and active. The cavity may thus be pumped out and entered for inspection, the pump's capacity being greater than the leaks.

In Fig. 1 it will be seen that the rudders are not in the same horizontal plane. This is for securing the greatest length of anchorage between journals 5 and 6 in the interior of the bulbous bow so as to aid the rudders in withstanding the heavy pressures involved in their action.

The connection 21 connecting with lever 11 should also be suitably packed as by a wobbling bellows form of packing shown at 60, this giving freedom for all its movements.

The operation of my invention is as follows: As the ship pitches downwardly, for instance, the pinion 37 will be rotated in a clockwise direction by reason of the gear 34 attached to the gyroscope standing still, thus rotating contact drum 38 clockwise. This will cause the trolley 39 to contact with the upper live sector, thereby setting the follow-up motor 42 into operation to rotate 125

the gear 40 so that the trolley will again be brought on to the insulated section 38'. As gear 40 rotates, drum 20 is carried with it, thereby moving the slip-friction clamp 19 clockwise to carry the arm 18 against upper stop 18'. The valve 12 is, therefore, moved downwardly to cause the piston in cylinder 10 to turn the rudders 1 and 1' counterclockwise to exert an upward torque on the bow. 5 The extent of movement of the fins is governed by the prevailing amplitude of pitch through the scissors mechanism 23, the scissors being opened by the oscillation of the pin 24 which is driven from the gear 40 through reduction gearing an amount proportionate to the prevailing amplitude of pitch. As soon as the direction of pitching motion reverses, the feather of the rudders is reversed, for just as soon as the direction 10 of pitch reverses the arm 18 is snapped against the lower stop 18'', thus reversing the valve 12. While I employ, therefore, a gyro pendulum having three degrees of freedom for controlling the rudders, the reversal 15 of the feathering does not wait until the ship passes through its level position but takes place as soon as the direction of the pitch of the ship takes place.

In case calm weather is encountered, the 30 fins may be withdrawn by turning the valve 51. This valve can only be turned as explained when the fins are in line with the slots 56, the locking mechanism 52, 53 and 54 lining up the fins before the valve 51 can 35 be turned.

In accordance with the provisions of the 40 patent statutes, I have herein described the principle and operation of my invention, together with the apparatus which I now consider to represent the best embodiment thereof, but I desire to have it understood that the invention can be carried out by other means. Also, while it is designed to use the 45 various features and elements in the combination and relations described, some of these may be altered and others omitted without interfering with the more general results outlined, and the invention extends to such use.

50 Having described my invention, what I claim and desire to secure by Letters Patent is:

1. The combination with a ship having a 55 bulbous bow, of a water-tight compartment in said bow, a pair of fins rotatably mounted in said compartment and extending without the bow on each side, and means for feathering said fins also mounted within said bulbous bow and said compartment.

30 2. The combination with a ship having a bulbous bow, of a water-tight compartment 55 in said bow, a pair of fins rotatably mounted in said compartment and extending without the bow on each side, means for feathering said 25 fins, and means for withdrawing said

fins within said compartment when not in use.

3. A stabilizer for reducing the pitching of ships comprising a pair of feathering diving rudders, a gyroscopic pendulum, pitch-responsive means adapted to be reversed upon reversal of direction of pitch, and means actuated by said responsive means upon a change in the direction of pitch of the ship with respect to said gyroscope for reversing the feather of the rudders to oppose the pitching motion. 70

4. A stabilizer for reducing the pitching of ships comprising a pair of feathering diving rudders, a gyroscopic pendulum, 80 pitch-responsive means adapted to be reversed upon reversal of direction of pitch, means actuated by said responsive means upon a change in the direction of pitch of the ship with respect to said gyroscope for 85 reversing the feather of the rudders to oppose the pitching motion, and means responsive to the amplitude of pitch for governing the amount of feathering.

5. The combination with a ship having a 90 bulbous bow, of a pair of fins rotatably mounted therein and extending without the bow on each side, means for feathering said fins, means for withdrawing said fins within said bulbous bow through slots in said bow, 95 and interlocking means for aligning said fins and slots before they can be moved inwardly.

6. A stabilizer for ships including a gyro-pendulum, contacts displaceable by relative movement of said gyroscope and ship, a follow-up motor driven therefrom, a slip-friction device oscillated by changes in the direction of rotation of said motor, feathering rudders for stabilizing the ship, a servo-motor for actuating the same, and a controller therefor actuated from said slip-friction connection. 100

7. A stabilizer for ships including a gyro-pendulum, contacts displaceable by relative movement of said gyroscope and ship, a follow-up motor driven therefrom, a slip-friction device oscillated by changes in the direction of rotation of said motor, feathering rudders for stabilizing the ship, a servo-motor for actuating the same, a controller therefor actuated from said slip-friction connection, and means actuated by the extent of rotation of said follow-up motor and operating on the connections between said device and said servo-motor for varying the motion imparted to said controller for the purpose specified. 110

8. The combination with a ship having a 125 bulbous bow, of a pair of fins rotatably mounted therein and extending without the bow on each side, means for feathering said fins, means for withdrawing said fins within said bulbous bow when not in use, and a 130

water-tight compartment enclosing portions
of both of said means.

9. A stabilizer for reducing the pitch of
ships, comprising a plurality of feathering
5 diving rudders, means responsive to the de-
gree of pitch, means responsive to the veloc-
ity of pitch, means for feathering said rudders
to oppose the pitching movements, and
means whereby said last-named means is con-
10 trolled jointly by said first two means.

In testimony whereof I have affixed my
signature.

ELMER A. SPERRY.
